UNITED STATES PATENT OFFICE.

ANTONE J. ADAMEK, OF ORIENT, SOUTH DAKOTA.

SICKLE-BLADE HOLDER.

Application filed March 13, 1922. Serial No. 543,352.

To all whom it may concern:

Be it known that I, ANTONE J. ADAMEK, a citizen of the United States, residing at Orient, in the county of Faulk and State 5 of South Dakota, have invented certain new and useful Improvements in Sickle-Blade Holders, of which the following is a specification, reference being had to the accompanying drawings.

10 It is the purpose of the present invention to provide an improved device of this character, for holding blades while sharpening them on a grind stone.

Another purpose is the provision of a 15 holder including a supporting frame to straddle the grind stone and to be mounted on the frame of the grind stone, and including a movable hanger universally connected to the supporting frame, to permit 20 the blade to be shifted to different positions relatively to the grind stone, whereby the teeth of the sickle blade may be sharpened, each on one side, and then each on its opposite side, that is to say beginning at one 25 end of the blade, until the opposite end of the blade is reached, and then shifting the blade in an opposite tilted position, and beginning at the other end.

Still another purpose is the provision of a 30 holder of this kind having means, whereby the grinding and sharpening of sickle blades may be greatly facilitated, for example the hanger may be adjusted at different positions, tilted on one side and then the other, 35 tilted rearwardly and downwardly, or forwardly and downwardly, there being yieldable means connecting the blade holding clamps and the hanger, so as to relieve the weight of the blade on the operator.

40 It is well known that sickle blades are more or less heavy, and it is very difficult to hold the blade in one's hand, and properly sharpen each tooth, and at the same time support the projecting end of the blade. In 45 other words the weight of the blade renders the manual holding of the blade very tiresome, which will prevent the teeth of the blade from being sharpened properly.

While the design and construction at 50 present illustrated and set forth are deemed preferable, it is obvious that as a result of a reduction of the invention to a more practical form for commercial purposes, the invention may be susceptible of changes, and 55 the right to these changes is claimed, pro-

vided they are comprehended within the scope of what is claimed.

The invention comprises further features and combinations of parts, as will be hereinafter set forth, shown in the drawings and 60 claimed.

In the drawings:—

Figure 1 is a view in perspective, showing the improved holder as applied to a frame of a grind stone, with a sickle blade 65 attached;

Figure 2 is an enlarged view in elevation of the hanger, showing the same in a tilted position;

Figure 3 is an enlarged detail view of one 70 of the clamps for the blade; and

Figure 4 is a sectional view of the blade showing the clamp applied.

Referring to the drawings, 1 designates the side supports of the grind stone frame, 75 and 2 denotes the arms of the supporting frame 3 for the holder. The arms 2 of the supporting frame straddle the grind stone, and their right angle extensions 4 (which are shaped to conform to the contour of the 80 side supports 1 of the grind stone frame) are secured to the supports 1 by means of the clamps 5. The supporting frame 3 has an upstanding post 6, on which a sleeve 7 is secured by a set bolt 8. An arm 9 projects 85 from the sleeve 7, and straddling the arm is a U-shaped casting 10, which is provided with an upstanding projection 11. The lower extremities of the sides of the U-shaped casting terminate in opposite sockets 90 12, which receive a spherical member 13, for the purpose of supporting the hanger 14 universally from the casting. A suitable bolt 15 passes through the sides of the casting, to clamp the sides together and securely 95 in contact with the arm 9. The sides of the casting are clamped close enough together, to permit the spherical member to move freely in the socket, whereby the hanger may move universally in various positions. 100

The hanger 14 comprises a tubular bearing 16, from which rises an arch 17. Projecting from the upper part of the arch and in a lateral direction, for instance toward the operator who occupies a position on the 105 seat of the grind stone frame, is a guide bracket 18, provided with a guide slot 19. The guide slot 19 receives the projection 11, to assist in holding the hanger in different positions, when shifted, for the purpose of 110

disposing the sickle blade in different positions on the grind stone. A handle 20 projects from the bracket, by which the operator may shift the hanger to different positions.

- A rod 21 is mounted to move through the tubular bearing 16, and depending from the ends of the rod 21 are springs 22, which are in turn connected to the chains 23.
- 10 Holding levers 24 of sickle blade clamps 25 are connected to suitable hooks of the chains 23, so that the weight of the sickle blade 26 (which is engaged with the two clamps 25) will cause the levers to bear upon and hold 15 the blade 26 in the clamps. The more the blade is moved downwardly, the tighter the clamping levers 24 engage and hold the blade. Also the heavier the blade, the tighter the clamping levers will secure it in 20 the clamps.

Obviously the rod 21 can be shifted through the tubular bearing, so as to permit the operator to begin sharpening the teeth of the sickle blade at one end and finish at 25 the opposite end. Also either end of the blade can be tilted downwardly, not only by shifting the hanger, but by stretching the springs. When the rod 21 assumes a central position relatively to the bearing 14, the 30 sickle blade may be depressed substantially on a level plane with relation to the grind stone, or it may be tilted. By a careful examination of the drawings it can be well understood how the blade and the hanger 35 can be shifted in various positions, either transversely of the operator, in tilted positions, or in a direction away from the operator.

The invention having been set forth, what 40 is claimed is:—

1. In a sickle blade holder, the combination with a supporting frame adapted to be supported upon a grind stone frame, of a hanger mounted for universal movement 45 on said supporting frame and provided with a guide slot operatively receiving said supporting frame, to guide the hanger when adjusted and to set the same in position after being adjusted, and means for adjustably, 50 operatively suspending a sickle blade from the hanger.

2. In a sickle blade holder, a base frame, a supporting frame mounted upon the base frame and provided with a guide projection, a hanger mounted for universal movement 55 on said supporting frame and having guide and holding connections with said projection, a member adjustably mounted on the hanger for transverse movement thereof, and means for operatively suspending a 60 sickle blade from said member.

3. In a sickle blade holder, a base, a supporting frame thereon and provided with an arm, a hanger mounted for universal movement on said arm and provided with 65 guide connections with said arm for guiding the hanger when shifted, and setting the same after being shifted, a member connected to the hanger for transverse shifting movement, and means for operatively suspending the sickle blade from the member. 70

4. In a sickle blade holder, a base, a supporting frame thereon provided with a projecting arm, a clamp mounted on the frame and provided with a projection, a hanger mounted for universal movement on the clamp and provided with a guide slot receiving said projection, for guiding the hanger when shifted universally, and setting the same after being shifted, a member 80 mounted for adjustable sliding connections on the hanger, and means for operatively suspending a sickle blade from said member. 85

5. In a sickle blade holder, a base, a supporting frame thereon provided with a projecting arm, a clamp mounted on the frame and provided with a projection, a hanger mounted for universal movement on the clamp and provided with a guide slot receiving said projection, for guiding the 90 hanger when shifted universally, and setting the same after being shifted, a member mounted for adjustable sliding connections on the hanger, and means for operatively suspending a sickle blade from said member, 95 said suspending means including clamps for clamping the sickle blade when being sharpened.

In testimony whereof I hereunto affix my signature.

ANTONE J. ADAMEK.
